UNITED STATES PATENT OFFICE.

FRANK CONRAD, OF MILWAUKEE, WISCONSIN.

DECK-SASH PIVOT MECHANISM.

1,073,738.

Specification of Letters Patent. Patented Sept. 23, 1913.

Application filed April 28, 1913. Serial No. 764,118.

To all whom it may concern:

Be it known that I, FRANK CONRAD, a citizen of the United States, residing at Milwaukee, county of Milwaukee, and State 5 of Wisconsin, have invented new and useful Improvements in Deck-Sash Pivot Mechanism, of which the following is a specification.

My invention relates to improvements in 10 deck sash pivot mechanism.

The object of my invention is to provide a form of construction which facilitates the removal and replacement of the sash but which securely retains the sash in position 15 against accidental displacement, regard being had for durability, ease of adjustment and convenience of manipulation.

In the drawings—Figure 1 is a fragmentary elevation showing the inner face of a 20 deck sash at one end and a portion of the frame to which my invention is applied. Fig. 2 is a sectional view of the deck sash and frame, showing my invention as it appears in use with the sash in closed position.

Like parts are identified by the same reference characters throughout both views.

The frame 1, deck sash 2, and segmental bracket 3, secured to the end bar of the 30 deck sash, may be of ordinary construction. A fixed supporting plate 5 is secured to the frame and provided at its lower end with a bearing member 6 having a recess 7 in its upper surface, adapted to receive the pivot 35 stud 8 with which all ordinary segmental brackets 3 are provided. The plate 5 is provided with outwardly projecting members 10, recessed at 11 to receive shouldered projections 12 carried by a removable plate 40 13. This plate 13 is provided with a foot piece 14 at its lower end, adapted to bear upon or hang directly above the pivot stud 8, so that when the plate 13 is held in normal position, the pivot stud 8 cannot be 45 disengaged from said socket 7.

A locking cam 15 is pivoted at 16 to the upper end portion of the fixed plate 5. This cam comprises an oval member, and the pivot 16 extends therethrough at one 50 side of its center, the other side of said member having a projection 17 which serves as a handle for rotating the cam upon the pivot pin. The upper end of the plate 13 is provided with a rounded recess or depression 55 at 18, into which the member 15 may enter. When the wider portion of the cam

is in this recess 18, the plate 13 will be held in its normal position with the shouldered projections 12 in the recesses in the members 10, whereupon the upwardly projecting hook posts 20 on the members 10 will prevent the plate 13 from being dislodged. But by rotating the cam 15 to its inverted or dotted line position, illustrated in Fig. 2, the plate 13 may be removed for it may 60 then be lifted sufficiently to permit the shoulders 12 to pass over the hook posts 20.

A vertically movable rod 25 is provided with a forked member 26 at its lower end and an anti-friction roller 27 is journaled 70 in the fork arms and adapted to travel over the rounded projections or teeth 28 on the upper margin of segment 3. The arms of the fork 26 extend below the roller on opposite sides of segment 3 and coöperate in 75 holding the parts in place. The rod 25 extends through and is guided by the bracket arms 29 and 30. A coiled spring 31 is interposed between member 26 and arm 29, whereby the rod is forced downwardly and 80 the roller 27 pressed against the upper margin of the bracket 3. The reactionary pressure will tend to lift plate 13 by the pressure of the spring upon the arm 29 through which the rod 25 passes. But this upward 85 pressure will be resisted by the cam 15.

It will be observed that as the cam 15 is slightly oval in form, it will, when rotated from its normal position, first cause a slight depression of the plate 13 as the end of 90 the cam moves through the recess 18 at the top of said plate. But the continued movement of the cam brings its shorter radii into the recess, whereupon the pressure of spring 31 causes plate 13 to lift progressively until 95 it has been raised sufficiently to permit its removal. When the plate is removed, the foot piece 14 will, of course, no longer bear upon the pivot stud 8, and the sash 2 may thereupon be freely lifted and taken out. When the 100 sash is replaced, plate 13 will be re-inserted in position and depressed against the tension of the spring 31, either preparatory to the rotation of cam 15 to normal position, or by the pressure of said cam thereon when 105 being rotated to such position. Owing to the fact that when the cam reaches normal position a slight lifting movement of the plate 13 is permitted, it is obvious that no accidental disengagement is possible, for 110 the upward pressure of the plate upon the cam will hold the latter in its normal posi-

tion and the resistance of the cam to the pressure of the plate will hold the plate in position, the foot piece 14 also holding the pivot stud in position in its bearing.

5. I claim—

1. The combination with the stationary frame of a deck sash, of a set of projecting recessed members supported therefrom, a movable member socketed in said projecting members and adapted to be disengaged therefrom by a lifting movement, a locking device supported from said frame in a position to normally retain said movable member in position, and a spring actuated rod carried by said movable member and adapted to travel along the margin of a toothed segmental bracket carried by the deck sash.
- 10 2. The combination with the stationary frame of a deck sash, of a set of projecting recessed members supported therefrom, a movable member socketed in said projecting members and adapted to be disengaged therefrom by a lifting movement, a locking device supported from said frame in a position to normally retain said movable member in position, and a spring actuated rod carried by said movable member and adapted to travel along the margin of a toothed segmental bracket carried by the deck sash,
- 15 30 3. The combination with the stationary frame of a deck sash, of a set of projecting recessed members supported therefrom, a movable member socketed in said projecting members and adapted to be disengaged therefrom by a lifting movement, a locking device supported from said frame in a position to normally retain said movable member in position, and a spring actuated rod carried by said movable member and adapted to travel along the margin of a toothed segmental bracket carried by the deck sash, said movable member being provided with a downward extension adapted to retain a deck sash pivot stud in an open bearing member.

- 35 40 45 3. The combination with the stationary frame of a deck sash, of a set of projecting recessed members supported therefrom, a movable member socketed in said projecting members and adapted to be disengaged therefrom by a lifting movement, a locking device supported from said frame in a position to normally retain said movable member in position, and a spring actuated rod carried by said movable member and adapted to travel along the margin of a toothed segmental bracket carried by the deck sash, said spring actuated rod being provided with an anti-friction roller adapted to travel over the marginal teeth of said segmental bracket.

- 50 55 4. The combination with the stationary frame of a deck sash, of a set of projecting recessed members supported therefrom, a movable member socketed in said projecting members and adapted to be disengaged therefrom by a lifting movement, a locking device supported from said frame in a position to normally retain said movable member in position, and a spring actuated rod

carried by said movable member and adapted to travel along the margin of a toothed segmental bracket carried by the deck sash, said spring actuated rod being provided with an anti-friction roller adapted to travel over the marginal teeth of said segmental bracket, and said rod also having a forked member adapted to straddle the margin of said bracket.

5. The combination with a deck sash frame, a deck sash provided with a segmental bracket having a pivot stud, of a fixed member secured to the frame and provided with an open bracket for said pivot stud, a removable plate having socketed connection with said fixed member and adapted to be disengaged therefrom only by a lifting movement, said plate having a rounded recess in its upper end, a cam rotatably pivoted to said fixed member and having its margin engaged in said recess, a spring actuated rod supported by said movable plate with one end adapted to travel upon the margin of the sash bracket, said plate being lifted by the reaction of the spring against said cam, and said cam in one position being adapted to prevent a removal of the plate from the fixed member.

6. The combination with a deck sash frame, a deck sash provided with a segmental bracket having a pivot stud, of a fixed member secured to the frame and provided with an open bracket for said pivot stud, a removable plate having socketed connection with said fixed member and adapted to be disengaged therefrom only by a lifting movement, said plate having a rounded recess in its upper end, a cam rotatably pivoted to said fixed member and having its margin engaged in said recess, a spring actuated rod supported by said movable plate with one end adapted to travel upon the margin of the sash bracket, said plate being lifted by the reaction of the spring against said cam, and said cam in one position being adapted to prevent a removal of the plate from the fixed member, said plate being also provided with a downward extension adapted when in normal position to prevent the disengagement of the pivot stud from said open bearing.

In testimony whereof I affix my signature in the presence of two witnesses.

FRANK CONRAD.
